UNITED STATES PATENT OFFICE

2,054,178

MEANS TO PREVENT FLIGHT OF IMPROPERLY CHANGED SHUTTLE

Richard Greenleaf Turner, Worcester, Mass., assignor to Crompton & Knowles Loom Works, Worcester, Mass., a corporation of Massachusetts

Original application September 13, 1933, Serial No. 689,209. Divided and this application July 16, 1934, Serial No. 735,319

4 Claims. (Cl. 139—234)

This is a division of my prior application Serial No. 689,209, filed September 13, 1933.

In multicolor shuttle changing looms it is convenient to arrange the stacks of reserve shuttles in one magazine with a common delivery throat or compartment through which the reserve shuttles of the different stacks move during or preparatory to the shuttle changing operation. In the form of invention set forth in the aforesaid application I show front and back cells or stacks with the common compartment located under the front cell and in front of the lowest shuttle in the back cell. The latter shuttle is forced positively into the compartment and slides along a supporting platform, being guided by clips or the like which extend around the ends of the shuttles. The bottom shuttle of the front cell is required to fall through a distance somewhat greater than its own height, and there is an opportunity for it to rotate, in which case it may reach the compartment on its side.

In order to prevent this undesired rotation of the front reserve shuttles I have provided means for advancing the bottom shuttle of the rear stack so that the front wall thereof will lie practically in the same plane as the rear wall of the descending front shuttle, mutual engagement of the shuttles preventing rotation.

When the rear cell is empty, there is no engagement such as just described, and I have proposed in the application mentioned to extend the clips to such a position as will enable them to engage a rear ruled surface of the falling shuttle. Should the clips fail to operate as already described there is the possibility that a shuttle may enter the transferring shuttle box on the lay with one of its sides down. This might happen also if the operator should inadvertently place one of the shuttles on its side when supplying the stack with fresh shuttles. Under these conditions it would be quite desirable to prevent the shuttle from being picked out of the box, or at least picked into the shed.

It is accordingly an important object of my invention to provide a stop on the shuttle box or lay so located as to permit the full sweep of the picker stick, but effective to prevent the shuttle from completing its flight across the loom. This device may be rendered operative by the fact that the front and back dimension of the shuttle is greater than its height, so that when the shuttle is improperly located on its side the upper edge thereof projects high enough to engage the stop.

With these and other objects in view which will

appear as the description proceeds, my invention resides in the combination and arrangement of parts hereinafter described and set forth in the claims.

In the accompanying drawing, wherein a convenient embodiment of my invention is set forth,

Fig. 1 is a detailed transverse section taken through the lower part of the shuttle changer magazine and the upper part of the lay, showing the boxes for effecting shuttle change, a reserve shuttle being shown in the act of delivery from the compartment,

Fig. 2 is a horizontal section on line 2—2 of Fig. 1,

Fig. 3 is a detailed front elevation taken in the direction of arrow 3, Fig. 1, showing diagrammatically the relation of the shuttle boxes and the picking motion, and

Fig. 4 is a detailed section on line 4—4 of Fig. 2.

Referring to the drawing, I have shown a stationary magazine M having two stacks of shuttles F and R which are respectively at the front and rear of the magazine. A delivery finger 10 is movable about an axis 11 to release the bottom shuttle of the front stack. A clamp 12 acts to engage the shuttle immediately above the bottom one to prevent the descent of the superimposed shuttles of the front stack when the finger 10 moves to the dotted line position shown in Fig. 1.

A plunger head 15 actuated through a rod 16 cooperates with the bottom shuttle of the rear stack and extends through the rear wall 17 of the magazine. A lever 18 pivoted at 19 is actuated by mechanism not shown when it is desired to advance a shuttle from the rear stack to compartment C under the front stack. A light spring 20 serves to return the lever and plunger head to normal rear position.

The head 15 has two arms 21 and 22, respectively, each of which has a forwardly and downwardly beveled surface 25, as shown more particularly in Fig. 1. This bevel extends down to a vertical surface 26 on the head located to engage the rear wall of the bottom shuttle in the rear stack.

The two stacks are separated by a partition 30 having a front surface 31 in line with the front of the bottom shuttle of the stack R. The advance movement of the latter shuttle when descending along surface 25 results in this alignment. When so located the shuttle at the bottom of the rear stack will engage the rear surface of a falling shuttle from the front stack and cause the same to move correctly to an up-

right position, such as indicated in dotted lines in Fig. 1.

5 So long as there is a reserve shuttle in the cell or stack R, the falling front shuttles will be guided as described, but when the rear stack is empty, it is desirable to have additional means to regulate the movements of the front shuttles. This result may be accomplished by the use of a guard 35 which is secured by screws 36 to the plunger 10 head 15. The guard is extended on each side of the head and is bent as shown in Fig. 2 to conform more or less to the shape of the shuttles. The forward ends of the brace are bent toward each other as at 37 to form clips the front edges 15 of which as shown at 38 are substantially vertical to engage the rear wall of the front shuttles at points sufficiently removed from the shuttle tips to prevent shuttle rotation. The section shown in Fig. 4 illustrates a convenient relation of the 20 holder with respect to that part of a shuttle having a straight vertical surface, the edges 38 lying against the ruled surface 39 of the shuttle.

The guide 35, being mounted on the head 15, moves forwardly with the latter so that the extensions 37 move forwardly with an advancing rear shuttle and do not interfere with it.

The lay L may have top and bottom boxes 40 and 41, which as set forth in the aforesaid application, are raised during the shuttle changing operation so that the pivoted cover 42 of the top box can be elevated sufficiently to make a clear passage through the top of the upper box into which the shuttle in the compartment C may fall. Rearwardly extending supporting fingers 43 may be secured to the lay and support the shuttle in the compartment C until the top box arrives in rear position to receive the shuttle. These fingers 43 form no part of my present invention, but are substantially the same in structure and function as those shown in co-pending application Serial No. 560,573.

No. 368,781.
The matter thus far described operates normally to require a shuttle moving from the magazine into the top box 40 to retain its proper position so that weaving can continue after the shuttle change. The clip or guard 35 is claimed in application Serial No. 689,209, of which this is a division.

If the shuttle enters the box improperly and should rest on its side, proper weaving cannot ensue and it is desirable under these conditions to stop the loom, and the means for accomplishing this result forms the subject matter of the present application. By preventing delivery of the shuttle from the box, the weft stop motion not shown but well understood can act to prevent weaving by stopping the loom. The picking operation normally occurs before the filling fork comes into action and in order to prevent breakage of the picker stick it is desirable to place the shuttle arrester so that it will not engage the shuttle until the stick has had its full unobstructed movement.

In carrying out my invention I place a stop 50 as shown in Fig. 3 on the lay sword 51 so that the lower curved surface thereof is at such a distance above the race 52 as to prevent complete picking of a shuttle which is on its side by the picker stick P, but permitting uninterrupted delivery of a shuttle which is properly resting on its bottom. In other words, the distance between the race and the stop 50 is slightly greater than the height of the shuttle but less than its breadth, and is also located about a shuttle length from the inner end of the sweep of the picker stick.

As shown more particularly in Fig. 3, the bottom of stop 50 lies below the side 60 when the shuttle is on its side, but above the top of the shuttle when the latter is on its bottom, as suggested by dot and dash line 65, Fig. 3. The normal working stroke of the picker stick P is such that it is substantially completed before stop 58 brings the misplaced shuttle to rest.

The resistance to shuttle motion offered by the stop or means 50 will result in loom stoppage by the usual devices so that the incorrectly transferred shuttle can be inserted properly by hand. Either the filling stop motion or the protector mechanism can be relied upon to stop the loom. Failure of the shuttle to lay weft will operate the filling stop motion, and failure of the shuttle to arrive at the opposite side of the loom at the proper time will cause the protector to stop the loom.

From the foregoing it will be seen that I have 20 provided means for preventing an improperly changed shuttle from becoming active. While the shuttle is in transit from a front cell to the box 40 means are provided either by means of a shuttle in the back cell, or by surfaces independent of the back shuttles, to engage the front moving shuttle and prevent rotation thereof on its axis. Should the shuttle turn over while moving from the magazine, the stop 50 will prevent the shuttle from being picked into the shed, 30 after which well-known stopping mechanism will act to arrest the loom so that the defect may be corrected by the weaver.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom, a lay, a picker moving through a given range of action, a magazine for reserve shuttles, a shuttle box on the lay to receive from the magazine a shuttle either on its bottom or side, and a stop on the lay to engage a shuttle placed improperly in the shuttle box and on its side as a result of a faulty movement of the magazine from the shuttle box, said stop being located a distance from the near end of the range of action of the picker greater than the distance between that part of the shuttle engaged by the picker and that part engaged by the stop. 50

2. In a shuttle changing loom having a magazine of reserve shuttles each of which is of greater width than height, a lay with a shuttle race, a shuttle box on the lay to receive a reserve shuttle from the magazine, a picker stick having a picking stroke to drive a shuttle placed into the shuttle box out of the latter, and a stop located above the shuttle race a distance less than the width of the shuttle and greater than the shuttle height, said stop located to engage a misplaced shuttle with the width thereof vertical and at a distance along the lay from the shuttle box sufficient to permit the picker stick to have substantially a complete picking stroke before engaging a misplaced shuttle for the purpose of preventing the shuttle from entering the shed of the loom. 55 60 65

3. In a shuttle changing loom, a lay, a picker moving through a given range of action, a magazine for reserve shuttles, a shuttle box on the lay to receive a shuttle resting either on its bottom or its side, and a stop on the lay at the magazine end of the loom to engage a shuttle which is resting on its side as a result of faulty movement from the magazine to the shuttle box. 75

said stop being located to engage the shuttle after the picker has moved through substantially its given range of action.

4. In a shuttle changing loom having a magazine with reserve shuttles each having a width greater than its height, a shuttle race, a shuttle box to receive a reserve shuttle from the magazine and capable of holding a shuttle which rests either on its bottom with the height vertical or 10 on its side with the width vertical, means having a given range of movement to pick the shuttle out

of the box whether it be on its side or bottom, and means along the path of the shuttle located above the race sufficiently to be out of the path of a shuttle on its side but positioned to resist movement along the path of a shuttle on its side 5 when the means to pick has reached the end of its range of movement, the shuttle being stopped due to the resistance offered by the last named means to the shuttle on its side.
